COMBINATION SURFER AND TOBOGGAN

John Belik, 915 S. Jenifer St., Glendora, Calif. 91740

Filed July 30, 1969, Ser. No. 18,480

Term of patent 14 years

Int. Cl. D21—03

U.S. Cl. D71—1

FIG. 1

FIG. 2

FIG. 3

FIG. 4

FIG. 5

FIG. 7

FIG. 8

FIG. 9

FIG. 10

FIG. 6

FIG. 1 is a top view of a combination surfer and toboggan, showing my new design;

FIG. 2 is a side elevational view thereof;

FIG. 3 is a bottom view thereof;

FIG. 4 is a side elevational view of the side opposite that shown in FIG. 2;

FIG. 5 is a front view thereof;

FIG. 6 is a rear view thereof;

FIGS. 7, 8, 9 and 10 are sectional views taken at the correspondingly numbered section lines in FIG. 3.

I claim:

The ornamental design for a combination surfer and toboggan, as shown.
